UNITED STATES PATENT OFFICE

161,859

METAL EDGING STRIP

Frank Morrow, Johnston, R. I.

Application May 25, 1950, Serial No. 10,152

Term of patent 7 years

(Cl. D54—2)

To all whom it may concern:

Be it known that I, Frank Morrow, a citizen of the United States, residing at Johnston, in the county of Providence and State of Rhode Island, have invented a new, original, and ornamental Design for a Metal Edging Strip, of which the following is a specification, reference being had to the accompanying drawing, constituting a part hereof:

Fig. 1 is a side view of a metal edging strip showing my new design;

Fig. 2 is a top plan view thereof; and

Fig. 3 is an end view thereof.

I claim:

The ornamental design for a metal edging strip, substantially as shown.

FRANK MORROW.
